ART OF PRODUCING SEWED GARMENTS

Max Popper, Brooklyn, N. Y., assignor to Top-stitch Machine Corp., New York, N. Y., a corporation of New York

Application October 24, 1934, Serial No. 749,724

17 Claims. (Cl. 112—262)

This invention is directed broadly to a method of producing a pinked and topstitched seam for sewed articles, wherein the edge portions of two sections of fabric are upturned and simultaneously pinked and then downfolded with the pinked edges facing respectively in opposite directions and sewed together with a topstitch to form a practically flat puffed seam by a single passage through a combined pinking and sewing machine.

An object of this invention is to provide a puffed and topstitched seam with the puffed edges facing respectively in opposite directions and by a single passage through a combined pinking and sewing machine.

Another object of this invention is to provide a puffed and topstitched seam in successive steps of upturning, pinking and downfolding the edges of two sections of fabric with the puffed edges facing respectively in opposite directions and then stitching together the folded edges of the two sections of fabric by a single passage through a combined pinking and sewing machine and form a uniformly symmetrical and superiorly ornamented elastic seam with zig-zag stitching for sewed articles.

With the above and other objects in view, the invention will be hereinafter more particularly described and the successive steps required to carry out my method will be more fully disclosed.

In the drawings which show by way of illustration one embodiment of the seam and the steps of the method of making the same, Figure 1 is a perspective view showing the manner of placing, upturning, pinking, downfolding the edges of the sections of fabric with the puffed edges respectively facing in opposite directions and uniting the folded edges by zig-zag topstitching, in successive steps and in one continuous operation.

Figure 2 is a sectional view taken as on line 2—2 in Figure 1.

Figure 3 is a sectional view taken as on line 3—3 in Figure 1.

Figure 4 is a sectional view taken as on line 4—4 in Figure 1.

Figure 5 is a cross-sectional view of a modified puffed and topstitched seam, wherein the puffed fabric edges are in superposed relation and all the stitch lines pass through four layers of fabric.

Figure 6 is a plan view of the folder.

Figure 7 is a side view of the folder set in the base-plate.

Figure 8 is a sectional view of the folder, the section being taken as on line 8—8 in Figure 6.

Referring more in detail to the drawings, the method is carried out as follows: Two fabric sections 10 and 11 are positioned flat and in juxtaposed relation on the base plate 12 of a combined pinking and sewing machine (not shown). The sections 10 and 11 have their edges 13 and 14 upturned to fit into guideways 15 and 16 of a folder 17. The upturned edges 13 and 14 are presented to a pinking mechanism 18. The pinking mechanism 18 preferably comprises a rotary cutter 19 having a zig-zag cutting surface and resiliently pressed in any suitable manner against the outer surface of a rotatably mounted ball bearing or disk 20. The pinking mechanism 18 grips the upturned edge portions 13 and 14 of the fabric sections 10 and 11 and feeds them towards the needle 21 of the combined pinking and topstitch sewing machine. The upturned edges 13 and 14 are simultaneously puffed during the movement through the pinking mechanism and are then folded down with the puffed edges facing respectively in opposite directions by a duplex hemming section 22 of the folder 17 and united together by topstitching 23. The stitching is preferably of the zig-zag type, the fabric being pierced successively in two different and slightly spaced longitudinal lines, the threads of the stitches extending from one line to the other at uniform angles which permits the seam to yield when the fabric sections are stretched, without any danger of tearing the thread.

The seam as illustrated in Figure 4, shows the edge portions 13 and 14 of the fabric sections 10 and 11 folded flat and facing respectively in opposite directions. These folds form reinforcements against raveling. The stitching goes through a plurality of layers of fabric and reinforces the seam because any tendency to pull the seam apart causes the strain to act in the direction of the folded edges instead of against the selvage edges as heretofore. The seam shown in Figure 4 is stronger than an ordinary puffed seam wherein the sections of fabric are stitched together while lying face to face.

When two layers of fabric are puffed and stitched with the fabric sections lying flat and face to face, the stitches are visible only on the left sides of the fabrics, that is, on the normally concealed surfaces of the garments. However, when two layers of fabric are puffed and stitched with folded layers, as shown in Figure 4, the stitches are visible on the left or normally concealed side as well as on the right or normally

exposed side of the fabrics and such a stitch is termed by the art a topstitch, because the stitches are visible on the top face of the fabric sections.

When the type of seam shown in Figure 4 is made by two sewing operations, i. e., first a combined seaming and pinking operation and then a separate topstitch operation, it is practically impossible to provide uniformly parallel lines of stitching and uniformly parallel lines of pinking and stitching. My method makes it possible not only to produce the seam in one operation, but in addition provides perfectly parallel and uniform lines of pinking and stitching.

It is to be noted that the stitching together of the two sections of fabric may be done with a single needle or with a multiple needle zig-zag sewing machine, as illustrated in Figure 1. These various kinds of stitching may be produced on a sewing machine well known to the art as a "Singer 107W" or any other similar machine may be used when equipped with my device shown in Figure 1.

As shown in Figures 1 and 4, it will be noted that some of the stitches 24 pass through two layers of fabric section 10 and other of the stitches 25 pass through two layers of fabric section 11. It is also to be noted that the stitching, whether single or multiple zig-zag stitch, may be directed to pass through two layers of fabric as shown in Figures 1 and 4, or through four layers of fabric as shown by the stitch lines 24', 25', in Figure 5, wherein the folded edges are in superposed relation.

As best shown in Figures 6 and 7, the folder 17 is provided with a thin central rib 26 which may be secured to the guideway member 27 intermediate the guideways 15 and 16. The rib 26 preferably slopes down or changes elevation from the upper elevation of the guideway member 27 and terminates in a line with the point of exit 28 of the duplex hemming section 22 and as close to the needle 21 as possible. The rib 26 extends substantially down to the base-plate 12. The folder 17 also comprises two plates 29 and 30 fastened to the guideway member 27 and positioned in a horizontal plane parallel with and in spaced relation from the base-plate 12. The plates 29 and 30 are spaced away from the rib 26 forming longitudinal openings to permit the fabric sections 10 and 11 to enter between said plates and the base-plate 12 and to turn upwards, the turned edges 13 and 14 on emerging from the guideways 15 and 16 being then constrained to follow the rib 26 on respective sides thereof till the point of exit 28 from the hemming section 22 of the folder 17, when the pinked edges are curved at the tongues 33 and then flattened in the slot-like passages 34.

It is to be noted that the two sections of fabric 10 and 11 are positioned on the base-plate 12 of the sewing machine with the normally exposed surfaces of the fabric sections in direct contact with said base-plate.

It is also to be noted that when the seam herein described is incorporated in shadowproof or panel garments, that there will be a plurality of superposed sections of fabric on each side of the seam and the stitching shown in Figures 1 and 4 will pass through four layers of fabric while the stitching shown in Figure 5 will pass through eight layers of fabric.

I may position the pinking mechanism 18 substantially in line with the needle so as to perform the pinking and stitching operations simultaneously.

In order to remove the pinked clippings from the line of stitching and away from the pinking mechanism, I may provide an air compressor (not shown) and terminating in an air line 31 preferably positioned close to the exit end of the pinking mechanism 18. A jet of compressed air may thus be directed crosswise to the line of pinking to blow the pinked clippings out of the way of the line of stitching.

In operation, the edges of the juxtaposed fabric sections are first turned up and pinked, the pinked edges are then downfolded with the pinked edges respectively facing in opposite directions and sewed together to form a flat pinked and topstitched seam. This makes an ornamented and reinforced elastic seam which can be very readily made by a combined pinking and zig-zag sewing machine in one continuous operation.

It is to be noted that by the term "flat, edge-folded, seam" is meant a seam which has no hollow formation at the folded edge and wherein the folded layers are drawn together taut by the stitches which go through and across the line of seam formation, as best shown in Figure 4.

An elastic seam of the nature herein described is very desirable for making ladies' silk underwear and similar garments of fine texture, where it is necessary to reinforce the seam to secure additional strength because very delicate fabrics are employed for such garments.

I claim:

1. The method of forming a flat, edge-folded, ornamented and non-raveling elastic seam for sewed articles, which comprises turning up the edges of two flat sections of fabric into adjoining relation, in pinking both upturned edges simultaneously, in downfolding both pinked edges on said fabrics with the folded edges facing respectively in opposite directions and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.

2. The method of forming a flat, edge-folded, ornamented and non-raveling elastic seam for sewed articles, which comprises turning up the edges of two flat sections of fabric into adjoining relation, in pinking both upturned edges, in downfolding both pinked edges on said fabrics with the folded edges facing respectively in opposite directions, in causing said pinked edges to lay flat in superposed relation and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.

3. The method of forming a flat, edge-folded, ornamented and non-raveling elastic seam for sewed articles, which comprises turning the edges of two flat sections of fabric into adjoining relation with each other and in angular relation with said sections, in pinking both upturned edges simultaneously, in folding the pinked edges on

- said fabrics with the folded edges facing respectively in opposite directions, in causing said pinked edges to lay flat in superposed relation and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.
4. The method of forming a flat, edge-folded, ornamented and non-raveling elastic seam for sewed articles, which comprises turning up the edges of two sections of fabric into adjoining relation, in pinking both upturned edges simultaneously, in downfolding and causing said pinked edges to lay flat and facing in opposite directions and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.
5. The method of forming a flat, edge-folded, ornamented and non-raveling elastic seam for sewed articles, which comprises turning the edges of two flat sections of fabric into adjoining relation with each other and in angular relation with said sections, in pinking both turned edges simultaneously, in folding the pinked edges on said fabrics with the folded edges respectively facing in opposite directions, in causing said edges to lay flat in superposed relation and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.
6. The method of forming a flat, edge-folded, ornamented and non-raveling elastic seam for sewed articles, which comprises placing two sections of fabric on the base-plate of a sewing machine in juxtaposed relation, in turning the edges of said sections of fabric into adjoining relation with each other and in angular relation with said sections, in pinking both turned edges simultaneously, in folding the pinked edges with the pinked portions respectively facing in opposite directions and causing said edges to lay flat in superposed relation and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.
7. The method of forming a flat, edge-folded, ornamented and non-raveling elastic seam for sewed articles, which comprises placing two sections of fabric flat on the base-plate of a sewing machine with their respective edges on each side of the needle, in turning the edges of said sections of fabric into adjoining relation with each other and in angular relation with said sections, in pinking both turned edges simultaneously, in folding the pinked edges with the pinked portions respectively facing in opposite directions and causing said folded edges to lay flat in superposed relation and then stitching said edges together by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.
8. A pinked and overedge zig-zag stitched seam for sewed articles, comprising two sections of fabric, each section having a pinked and downfolded flat edge, the folded edge of one section of fabric lying flat in superposed relation on the other section of fabric and being stitched together by a single line of zig-zag stitches passing through both folded edges of said sections of fabric, both of said edges being transversely ornamented with V-shaped cuts visible on one side of the sewed article, both of said ornamented edges extending sideways from said stitched portion and forming a flat, edge-folded, non-raveling and elastic seam with zig-zag stitches passing through the folded sections of fabric.
9. A pinked and overedge zig-zag stitched seam for sewed articles, comprising two sections of fabric, each section having a pinked and downfolded flat edge, the folded edge of one section of fabric lying flat in superposed relation on the other section of fabric and being stitched together by a single line of zig-zag stitches passing through both folded edges of said sections of fabric, both of said edges being transversely ornamented with V-shaped cuts visible on one side of the sewed article, both of said ornamented edges extending sideways from said stitched portion and forming a flat, edge-folded, non-raveling and elastic seam with zig-zag stitches passing through the folded sections of fabric.
10. A pinked and overedge zig-zag stitched seam for sewed articles, comprising two juxtaposed sections of fabric, each section having a pinked and folded flat edge, the folded edge of one section lying flat in superposed relation on the other section of fabric and being stitched together by a single line of zig-zag stitches passing through both folded edges of said sections of fabric, both of said edges being transversely ornamented with V-shaped cuts visible on one side of the sewed article, both of said ornamented edges extending sideways from said stitched portion and forming a flat, edge-folded, non-raveling and elastic seam with zig-zag stitches passing through the folded sections of fabric.
11. A pinked and overedge zig-zag stitched seam for sewed articles, comprising two sections of fabric, each section having a pinked and downfolded flat edge, said folded and pinked edges lying flat and facing in opposite directions on said sections of fabric and being stitched together by a single line of zig-zag stitches passing through and across both folded edges of said sections of fabric, both of said edges being transversely ornamented with V-shaped cuts to prevent raveling.

- ing, both of said ornamented edges extending sideways from said stitched portion and forming a flat, edge-folded, ornamented and elastic seam with zig-zag stitches passing over the adjoining edges of the folded sections of fabric.
12. The method of forming a flat, edge-folded, ornamented and non-raveling elastic seam for sewed articles, which comprises placing a plurality of sections of fabric flat on the base-plate of a sewing machine with their respective edges on each side of the needle, in turning the edges of said sections of fabric into adjoining relation with each other and in angular relation with said sections, in pinking all of said turned edges, in folding the pinked edges with the pinked portions respectively facing in opposite directions and causing said folded edges to lay flat and stitching said edges together by topstitching passing through all of said sections of fabric and by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded, ornamented and elastic seam with zig-zag stitches passing over the adjoining edges of the folded sections of fabric.
13. The method of forming a flat, edge-folded, ornamented and non-raveling elastic seam for sewed articles, which comprises placing a plurality of sections of fabric flat on the base-plate of a sewing machine with their respective edges on each side of the needle, in turning the edges of said sections of fabric into adjoining relation with each other and in angular relation with said sections, in pinking all of said turned edges, in blowing the pinked clippings away from the line of stitching, in folding the pinked edges with the pinked portions respectively facing in opposite directions and causing said folded edges to lay flat and stitching said edges together by topstitching passing through all of said sections of fabric and by a single line of zig-zag stitching passing through and across both folded edges of said sections of fabric and causing both of said edges to be transversely ornamented with V-shaped cuts to prevent raveling, both of said ornamented edges extending sideways from said stitched portion and forming a flat, edge-folded,

ornamented and elastic seam with zig-zag stitches passing over the adjoining edges of the folded sections of fabric.

14. An edge-folded, trimmed and zig-zag stitched seam having all folded edges in contact with the normally concealed surface of the garment, comprising at least two sections of fabric, each section having a trimmed and downfolded flat edge, said folded and trimmed edges lying flat and facing in opposite directions on said sections of fabric and being stitched together by a single line of zig-zag stitching passing through the pre-folded edges of the folded sections of fabric and forming an edge-folded and trimmed elastic seam substantially flat on its normally exposed surface.

15. An edge-folded and zig-zag stitched seam having all folded edges in contact with the normally concealed surface of the garment, comprising at least two sections of fabric, each section having a downfolded flat edge, said folded edges lying flat and facing in opposite directions on said sections of fabric and being stitched together by a single line of zig-zag stitching passing through the pre-folded edges of the folded sections of fabric and forming an edge-folded elastic seam substantially flat on its normally exposed surface.

16. An edge-folded, trimmed and zig-zag stitched seam, substantially flat on its normally exposed surface, comprising at least two sections of fabric, each section having a trimmed and flat edge folded against the normally concealed surface of the garment, said folded and trimmed edges lying flat and facing in opposite directions on said sections of fabric and being stitched together by a single line of zig-zag stitching passing through the pre-folded edges of the folded sections of fabric.

17. An edge-folded and zig-zag stitched seam, substantially flat on its normally exposed surface, comprising at least two sections of fabric, each section having a flat edge folded against the normally concealed surface of the garment, said folded edges lying flat and facing in opposite directions on said sections of fabric and being stitched together by a single line of zig-zag stitching passing through the pre-folded edges of the folded sections of fabric.
